DESCRIPTION

Dec. 1, 1999 (IT) MI99O0708

FIG. 1 is a top plan view of a portion of ground coffee
compressed between two water-permeable paper elements,
showing my new design, the appearance of the side opposite
that shown in FIG. 1 being substantially the mirror image
thereof

(51) LOC (7) Cl. **01-01**

FIG. 2 is a side elevational view thereof, the appearance of
the side opposite that shown in FIG. 2 being the mirror
image thereof; and,

(52) U.S. Cl. **D1/199**

FIG. 3 is a perspective view thereof.
